CLAIM

The ornamental design for a dance footwear, as shown and described.

DESCRIPTION

FIG. 1 is a front right perspective view of dance footwear showing my new design in use condition;

FIG. 2 is a front view thereof;

FIG. 3 is a rear view thereof;

FIG. 4 is a right side elevation view thereof;

FIG. 5 is a left side elevation view thereof;

FIG. 6 is a top view thereof; and,

FIG. 7 is a bottom view thereof.

The broken line showing of the foot is for illustrative purposes only and forms no part of the claimed design.

1 Claim, 5 Drawing Sheets
